UNITED STATES PATENT OFFICE.

BYRON E. WILSON, OF MARION, OHIO, ASSIGNOR TO THE EYMON CROSSING COMPANY, OF MARION, OHIO, A CORPORATION OF OHIO.

RAILWAY CROSSING.

Application filed September 19, 1921. Serial No. 501,775.

To all whom it may concern:

Be it known that I, BYRON E. WILSON, a citizen of the United States, residing at Marion, in the county of Marion and State 5 of Ohio, have invented certain new and useful Improvements in Railway Crossings, of which the following is a specification.

My invention relates to railway crossings, and the object of the invention is to construct a railroad crossing of a most efficient and noiseless type, which will be subjected to a minimum amount of wear. It is particularly adapted to that type having uninterrupted tread portions for the connecting 10 rails, one form of which is illustrated in my prior Patent No. 1,321,691 issued Nov. 11, 1919.

It is usual in such constructions to employ a movable corner piece called a "block" 20 and this improvement is intended to protect that block against dirt and other obstacles that might otherwise tend to interfere with its proper movement.

In the drawings there is illustrated the 25 usual rectangular crossing, but the invention is adapted for use with other types of crossings and switches.

Fig. 1 is a plan view.

Fig. 2 is a section on line 2—2 of Fig. 1.

30 Fig. 3 is a section on the line 3—3 of Fig. 2.

Fig. 4 is a horizontal section of a guard rail showing the apertures, parts being broken away.

35 Referring to the drawing, the outgoing rails are indicated by the numerals 5 and 6, the set of rails 5—5 comprising the tracks of one road, while the rails 6—6 comprise the tracks of another road. The terminals 40 of the rails are indicated by 5^a and 6^a. The crossing proper is formed of rail sections 7 connecting with rails 5 and rail sections 8 connecting with rails 6.

The guard rails 10 form the balance of 45 the crossing which is shown with open spaces or gaps between the terminals 5^a and the rail sections 7 and the terminals 6^a and the rail sections 8.

The blocks 11 are slidably mounted in the 50 open spaces or gaps described in detail in my prior patent.

The operating lever 12 extends outwardly, as shown in Fig. 1, instead of inwardly as 55 in my prior patent, but these removable levers are formed with cams which operate

the blocks in the same manner as in said prior patent.

In order to protect the blocks 11 against interference from dirt and small obstacles accumulating in the spaces between the rails 60 and guard rails, there are formed in the webs of the guard rails apertures 13 which are shown extending outwardly and downwardly from the rails. These apertures are likewise shown (Figs. 1 and 4) flaring outwardly from said rails to insure the easy 65 passage of the dirt and small obstacles and prevent clogging.

It is apparent that the blocks 11 will co-operate with the apertures to keep the working surfaces between the blocks and guard rails open and clear of obstructions. The movement of the blocks in a diagonal direction, relative to the rail sections, is obviously advantageous in forcing the dirt 75 into said apertures.

Having thus described my invention, I claim:

1. In a railway crossing, the combination of rails and rail sections at the crossing, a 80 movable block for forming uninterrupted tread surfaces between the rails and rail sections, and apertures at the side of said block forming passageways for dirt and other obstacles, said apertures and movable 85 block being so arranged that the block will force dirt and small obstacles through said apertures, each of said apertures being widened in the direction of the outlet end thereof. 90

2. In a crossing, the combination of two sets of rails and rail sections at the crossings, one pair of rail sections co-operating with one set of rails, movable blocks normally in position whereby open spaces will 95 be formed between the rails and the blocks, but capable of being moved to closed position whereby they will form uninterrupted tread portions between said rails and said rail sections, apertures formed at the side 100 of said blocks and in line with same, means for moving the blocks and thereby forcing the dirt and other obstacles that are present in said open space through said apertures of a downwardly flaring type in relation to 105 the blocks.

3. In a crossing, the combination of two sets of rails and rail sections at crossings, one pair of rail sections co-operating with one set of rails, movable blocks normally in 110

position whereby open spaces will be formed between the rails and the blocks, but capable of being moved to closed position whereby they will form uninterrupted tread portions 5 between said rails and said rail sections, apertures formed at the side of said blocks and in line with same, means for moving the blocks and thereby forcing the dirt and other obstacles that are present in said open 10 space through said apertures of a downwardly flaring type and extending downwardly.

4. In a crossing, the combination of rails and rail sections, there being formed between the terminals of the rails and the terminals of the rail sections, open spaces or 15

gaps and movable blocks located in said spaces, means for oscillating said movable blocks in a diagonal direction with relation to said rails, leaving exposed open spaces in one position of said blocks whereby dirt will accumulate, apertures at the sides of said blocks capable of receiving the dirt and permitting the same to be forced therein by the said blocks, each of said apertures being 20 widened in the direction of the outlet end thereof. 25

In testimony whereof I have hereunto set my hand this fifteenth day of September 1921.

BYRON E. WILSON.
